(57) **CLAIM**

I claim the ornamental design for a display screen or portion thereof with a graphical user interface, as shown and described.

DESCRIPTION

The FIGURE is a front view of a display screen or portion thereof with a graphical user interface showing my new design.

The broken line showing of the display screen or portion thereof forms no part of the claimed design. The broken line showing of text and lighter broken line showing of portions of the graphical user interface form no part of the claimed design.

1 Claim, 1 Drawing Sheet
